US00D859341S

(12) **United States Design Patent** (10) **Patent No.:** **US D859,341 S**
(45) **Date of Patent:** **** Sep. 10, 2019**

(54) **MOBILE TERMINAL**

(71) **Applicant:** **SAMSUNG ELECTRONICS CO., LTD.**, Suwon-si, Gyeonggi-do (KR)

(72) **Inventors:** **Byung-Jin Kang**, Seoul (KR); **Do-Hyung Lee**, Yongin-si (KR); **Kyu-Hong Kim**, Yongin-si (KR)

(73) **Assignee:** **SAMSUNG ELECTRONICS CO., LTD.**, Gyeonggi-Do (KR)

(**) **Term:** **15 Years**

(21) **Appl. No.:** **29/622,601**

(22) **Filed:** **Oct. 18, 2017**

Related U.S. Application Data

(63) Continuation of application No. 29/559,841, filed on Mar. 31, 2016, now Pat. No. Des. 804,443.

(30) **Foreign Application Priority Data**

(57) **CLAIM**

The ornamental design for a mobile terminal, as shown and described.

DESCRIPTION

FIG. 1 is a perspective view of a mobile terminal showing our new design in an exemplary embodiment;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is another perspective view of FIG. 1 in a folded position;

FIG. 9 is a front view of FIG. 9;

FIG. 10 is a rear view of FIG. 9;

FIG. 11 is a left-side view of FIG. 9;

FIG. 12 is a right-side view of FIG. 9;

FIG. 13 is a top plan view of FIG. 9; and,

FIG. 14 is a bottom plan view of FIG. 9.

The broken lines illustrating portions of the mobile terminal form no part of the claimed design.

1 Claim, 10 Drawing Sheets
